United States Patent Office

Des. 220,312

Patented Mar. 30, 1971

220,312

BOTTLE

Dale K. Weber, East Lansing, Mich., assignor to Orchard Grove Company, Lansing, Mich.

Filed Mar. 9, 1970, Ser. No. 21,785

Term of patent 14 years

Int. Cl. D9—01

U.S. Cl. D9—100

FIG. 1 is a perspective view of a bottle showing my new design;

FIG. 2 is an elevational view thereof;

FIG. 3 is a top view thereof; and

FIG. 4 is a bottom view thereof.

I claim:

The ornamental design for a bottle, as shown.
